US00D826027S

(12) **United States Design Patent** (10) **Patent No.:** **US D826,027 S**
Carey et al. (45) **Date of Patent:** **** Aug. 21, 2018**

(54) **LATCH**

(71) **Applicant:** **THE METAL WARE CORPORATION**, Two Rivers, WI (US)

(72) **Inventors:** **Richard Carey**, Manitowoc, WI (US); **Ross Niemi**, Chicago, IL (US)

(73) **Assignee:** **The Metal Ware Corporation**, Two Rivers, WI (US)

(**) **Term:** **15 Years**

(21) **Appl. No.:** **29/608,071**

(22) **Filed:** **Jun. 19, 2017**

(51) **LOC (11) Cl.** **08-07**

(52) **U.S. Cl.**

USPC **D8/331**; D8/339; D8/343

(58) **Field of Classification Search**

USPC ..... D8/330, 331, 333, 339, 343, 344, 345, D8/349, 354, 355, 356, 367, 382; 70/14, 70/49, 58, DIG. 63, DIG. 35, 30, 51, 52, 70/57, 57.1, 141, 431, 465, 466, 29, 70/63–76, 78, DIG. 31, DIG. 26, DIG. 67; 292/288, DIG. 30, 292, 181–287, 292/DIG. 16, DIG. 53, DIG. 42; 24/458, 24/455, 572.1, 573.09, 265 R, 307 R CPC E05C 19/10; E05C 19/18; E05B 73/00; B25G 3/00; B25G 3/12

(57) **CLAIM**

The ornamental design for a latch, as shown and described.

DESCRIPTION

FIG. 1 is a perspective view of a latch showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a perspective view thereof, shown the latch in environmental use with the latch in an engaged position;

FIG. 9 is a perspective view thereof, shown the latch in environmental use with the latch in a released position;

FIG. 10 is another perspective view thereof, shown the latch in environmental use with the latch in an engaged position;

FIG. 11 is another perspective view thereof, shown the latch in environmental use with the latch in an engaged position;

FIG. 12 is another perspective view thereof, shown the latch in further environmental use with the latch in an engaged position; and,

FIG. 13 is another perspective view thereof, shown the latch in further environmental use with the latch in an engaged position.

The broken lines indicate the environment of a cooler in FIGS. 8–13 and form no part of the claimed design.

1 Claim, 13 Drawing Sheets
